UNITED STATES PATENT OFFICE.

SCOTT C. APPLEWHITE, OF SAN ANTONIO, TEXAS.

LIFTING-JACK.

1,168,994.

Specification of Letters Patent.

Patented Jan. 18, 1916.

Application filed June 17, 1915. Serial No. 34,667

To all whom it may concern:

Be it known that I, SCOTT C. APPLEWHITE, a citizen of the United States, residing at San Antonio, in the county of Bexar and State of Texas, have invented new and useful Improvements in Lifting-Jacks, of which the following is a specification.

The present invention relates to lifting jacks and more particularly to that type of jack which is adapted to be operated for lifting the vehicle by the momentum or movement of the latter.

The present invention contemplates a jack of novel and simple construction and which is void of any pawl and ratchet, or other hand-operated mechanism, for manually lifting the vehicle.

With the above in view, the invention consists in a substantially quadrantal segment being formed with an eccentric portion extending at a tangent to the segment and forming the lifting portion of the jack, and a removable and adjustable bearing head for the segment adapted to engage with the axle or suitable portions of the vehicle.

The invention further consists in the novel construction of the invention and in the combination of parts hereinafter more fully described and finally pointed out in the appended claims.

In the drawings which form part of the specification: Figure 1 is a side elevation of the invention illustrating the same placed in position preparatory to the lifting of the vehicle; Fig. 2 is a view similar to Fig. 1 showing the invention in operative position, or having lifted the vehicle and supporting the same in position; Fig. 3 is a perspective view of the invention showing the bearing head removed from the segment; and Fig. 4 is a detail sectional view taken on line 4—4 of Fig. 2.

Like reference characters denote similar like parts throughout the specification and drawings.

Referring particularly to the drawings, the lifting jack A consists of a quadrantal segment 1 being formed on one side of its enlarged end with an eccentric projection 2. The outer peripheral edge of the eccentric portion 2 is formed to extend at a tangent to the peripheral edge of the quadrant 1, as may be clearly seen from Figs. 1, 2 and 3. The quadrant 1 and the eccentric portion 2 are made of light metal and are provided upon their side edges with the reinforcing

ribs 3, which may be suitably secured to the quadrant and eccentric portion, however, in the present embodiment, the same is shown being formed integrally therewith. The upper ends of the reinforcing ribs 3 are integrally joined together to form, with the quadrant 1, a solid shank or supporting head 4; or, in other words, the ribs 3 diverge from the shank or solid supporting head 4 and form a continuation thereof to act as reinforcing ribs for the quadrantal segment 1 and the eccentric portion 2, which latter are preferably of light metal. The peripheral edge of the eccentric portion 2 and the quadrant 1 unite to form the bottom bearing surface of the jack. An angular foot piece 5, adapted to conform to the contour of the peripheral edge of the portions 1 and 2, provides an enlarged tread or bearing face for the base of the jack, which is adapted to be rocked therefrom when operatively placed for lifting. The foot or tread portion 5 may be suitably secured to the quadrant 1 and eccentric portion 2, however, as here shown, the same is formed integrally therewith and is rigidly connected to the reinforcing ribs 3. The bearing head 6 having one end bifurcated or formed with the right-angular recess, as shown at 7, is adapted to be removably and adjustably supported upon the supporting head 4 of the lifting jack. To more specifically describe the bearing head 6, it may be said that the same comprises a substantially rectangular body portion 6 having a bifurcated flared end, the walls 7 of the bifurcation being at right angles to each other and adapted to accommodate the hub or axle B of the vehicle, or other suitable part thereof. The bearing head 6 is further formed in its body portion with two parallel and opposed rectangular openings 8, each having a corresponding vertical edge thereof formed with a plurality of downwardly curved notches or teeth 9 extending for a distance into said openings. The supporting head 4 has projecting therefrom a pair of spaced lugs 10, preferably, of a cylindrical formation to be accommodated in the recesses formed between the curved notches 9. As will be seen from the drawings, each of the lugs 10 are, respectively, received in one of the openings 8 in the bearing head 6 and adjustably engage with the notches 9 to admit of said head 6 to be vertically adjusted upon the lifting jack A. By pro-

viding two sets of notches 9 and their corresponding supporting lugs 10, it will be seen that greater strength is produced and the peculiarly constructed bearing head 6 is prevented from rotating upon the jack A. The lugs 10 are further provided with the enlarged heads 11 which are of sufficient size to engage with the notches 9 and prevent the bearing head 6 from moving longitudinally with respect to the pins 10, consequently, holding the head 6 in a substantially fixed and rigid position.

It will thus be seen that the lifting jack is composed of two parts, namely; the adjustable bearing head 6 and the quadrantal segment supporting portions 1, and this particular construction admits of a ready adjustment and easy manipulation of the bearing head 6 upon the lifting jack A, it being apparent that no other manual adjustment or operation of the jack is necessary than to adjust the head 6 upon the supporting head 4 the desired distance to which the axle or other portion of the vehicle is to be elevated.

When the jack A is placed under an axle B of a vehicle or other suitable portion thereof, so that the axle is fitted in the bifurcated end of the bearing head 6, and so that the tread or base portion 5 of the jack rests on the ground or flooring, the vehicle can, of its own forward or backward motion, lift that portion of its structure that is above the jack; in other words, the vehicle jacks up itself after the jack has been suitably placed in a position as shown in Fig. 1. To jack up the front wheels of the vehicle, it is preferable to place the jack forward of the front axle and then, in the cases of automobiles, the power may be used for forwardly moving the vehicle which will instantly rock the jack upon its tread 5 and elevate the front portion of the vehicle. To jack up the rear wheels, the jack is placed in a similar manner behind the rear axle and then by a slight backward movement of the vehicle, the jacks will be rocked upon their treads 5 and the rear wheels of the vehicle will be elevated. Dismounting of the vehicle from the jacks may be accomplished by the mere pushing of the vehicle or by turning on the power of the latter reversely to that by which the vehicle was raised.

Having thus described the invention, it is believed that the foregoing is a clear and accurate description of the same and that a full understanding thereof may be had. However, it is to be understood that certain changes as to the precise construction and combination of parts may be resorted to that fall within the legitimate scope of the appended claims.

What is claimed is:

1. A device of the character described comprising a quadrantal supporting member being formed with an eccentric rocking portion adapted to engage with the ground, a bearing head formed with a bifurcated end adapted to engage with portions of a vehicle, said head being formed with a plurality of slots therein, a series of notches formed in each slot, and a plurality of lugs projecting from said supporting member and adapted to be adjustably received in the recesses formed between said notches for supporting said bearing head in position, said jack being adapted to raise the vehicle when the latter is rocked upon its eccentric rocking portion.

2. A jack for vehicles comprising a sheet metal supporting member being formed with an eccentric rocking portion adapted to engage the ground, a solid shank formed on said supporting member opposite said rocking portion, lugs projecting from one side of said shank and a bearing head formed with means for adjustable and removable engagement with said lugs and for supporting said head upon said shank.

3. In a device of the character described, comprising, a quadrantal supporting member formed with an eccentric rocking portion adapted to engage with the ground, a bearing head formed with a slot therein, a series of notches formed in said slot, and lugs projecting from said supporting member and adapted to be adjustably received in the recesses formed between said notches for supporting the bearing member in position.

In testimony whereof I have hereunto set my hand in presence of two subscribing witnesses.

SCOTT C. APPLEWHITE.
